GRILLE FOR A TRACTOR

Robert J. McKnight, Springfield, Ohio, assignor to Orly Musgrave, Springfield, Ohio

Application January 30, 1956, Serial No. 39,966

Term of patent 14 years

(Cl. D14—3)

I claim:

The ornamental design for a grille for a tractor, substantially as shown and described.
